DESIGN FOR A COMBINATION LOUVRE AND
DRIP MOLDING

Carl J. Wagner, Detroit, Mich.

Application February 12, 1946, Serial No. 126,519

Term of patent 14 years

(Cl. D14—6)

To all whom it may concern:

Be it known that I, Carl J. Wagner, a citizen of the United States of America, residing at Detroit, in the county of Wayne and State of Michigan, have invented a certain new, original, and ornamental Design for Combination Louvre and Drip Molding, of which the following is a specification, reference being had to the accompanying drawing, forming a part thereof.

Figure 1 is a perspective view of a combination louvre and drip molding, showing my new design;

Figure 2 is a side elevational view; and

Figure 3 is a somewhat enlarged cross-sectional view taken on the line 3—3 of Figure 1.

The dotted line showing in the drawing figures is for illustrative purposes only.

I claim:

The ornamental design for a combination louvre and drip molding, substantially as shown and described.

CARL J. WAGNER.
